LOUIS MUELLER, OF BERLIN-BAUMSCHULENWEG, GERMANY, ASSIGNOR TO ADOLF HAMM & CO., OF DUSSELDORF, GERMANY.

WHIRLING DEVICE FOR PLATES WITH LIGHT-SENSITIVE LAYERS.

Application filed March 8, 1924. Serial No. 697,973.

To all whom it may concern:

Be it known that I, LOUIS MUELLER, merchant, citizen of Germany, residing at Berlin-Baumschulenweg, in Prussia, Germany, have invented new and useful Improvements in a Whirling Device for Plates with Light-Sensitive Layers, of which the following is a specification.

In the whirling devices of known type for the uniform distribution and drying of light-sensitive layers on plates by centrifugal action the plates of glass, metal or other material are clamped above a rotatable cross by means of holders adjustable on the arms 10 of the cross, in such a manner that each holder grips the plate at the middle of the one side edge. The apparatus of this known type require therefore four separate plate holders which have to be adjusted separately. The insertion and removal of the plate demands consequently much time and is rather difficult. It has already been proposed to make the holders grip and hold the plates only at two opposite side edges; but 20 in this case there is always the danger that under the action of the centrifugal force the plate itself is thrown out of the holder and destroyed.

The present invention has for its object 30 to create a device which permits of a rapid clamping and releasing of the plate which is nevertheless held quite securely. With this object in view the holders grip and hold the plate at two diagonally opposite corners 35 so that a throwing of the plate out of the holders is impossible even when only two holders are provided. The arrangement is preferably of such a kind that two holders mounted in one guide frame grip and hold 40 the plates athwart. The inserting and releasing of the plates is thus facilitated and the possibility is obtained to combine the holders of every pair of holders to a vertical wire loop or wire ring into which the one 45 corner of the plate can be inserted from the side and in which the plate is held by contact merely at the edges of the plate. The one or both blocks or slides which carry the pairs of holders may be fitted with springs 50 which tend to pull the same towards the

pivot axis of the device and to ensure thereby automatically the clamping of the plate in the device.

Two embodiments of the invention are shown by way of example on the accompanying drawing in which:

Fig. 1 shows in side elevation the one embodiment of the invention.

Fig. 2 is a plan view of Fig. 1, and

Fig. 3 is a cross section, one of the slide- 60 ble blocks being shown in front elevation.

Fig. 4 is a plan view of the second embodiment of the invention.

Fig. 5 is a cross section of the device shown in Fig. 4, one of the slideable blocks 65 being shown in front elevation.

In the form of construction shown in Figs. 1 to 3 the guide arms 2 made from thick wire bent double extend opposite one another, radially from the vertical shaft 1 70 of the device. Two slideable blocks are mounted on the guide arms 2, one on each side of the shaft 1. The one of these slideable blocks is composed of two jaws 3 and 4 which embrace the guide arm 2 and are 75 tightly pressed on the same by a clamping screw 5. On the upper jaw 3 of this slideable block a vertical ring or loop 6 of wire is fixed. This ring or loop 6 is preferably slightly bent angularly at two opposite 80 points 7 so that at each of these points an angle is formed which serves for holding one of the edges of the plate.

The other slideable block 8 is loosely and 85 slidably mounted on the guide arm 2, and it also carries an upright wire ring or loop 6a. Between this slideable block 8 and the central beam of rotatable arms mounted on shaft 1 a spring 9 is arranged which has the tendency to pull the slideable block 8 towards 90 the centre. This spring might be adjustably arranged if desired so that it may be adapted to very different sizes of plates and the same device may be used for the whirling and drying of photographic plates and 95 the like of strongly different sizes.

To insert the plate 10 to be whirled into the device the slideable block 8 is pulled outward against the action of spring 9 whereupon one of the corners of plate 10 is in- 100

serted from the centre into the loop or ring 6 of the block 3, 4. The slidable block 8 is then released so that its loop or ring 6^a gets over the opposite corner of the plate 10, this 5 plate being thus securely held at two opposite corners as shown in Fig. 2, the angles 7 of the loops 6 and 6^a touching the plate only at its edges. It is obvious that the 10 holders do not in the least impede the casting away of the light sensitive mass in excess and as the plate also is not in touch with the holders at the lower side of the plate, the sensitive layer is quite uniformly 15 dried by the usual heating from below during the whirling of the plate. The result is that a plate treated in this device may be exposed up to its outer edges.

It will be clear from the above description how simply, easily and rapidly the clamping 20 of the plate in the device and the removing therefrom may be performed. The block 3, 4 needs to be adjusted on its guide arms 2 only when plates of another size are to be treated on the device. In this case an adjusting of the block 3, 4 is advisable in order 25 to be able to arrange the plate to be treated centrally to the shaft 1. In the devices of known type in which the plate is gripped at four points of the edges four slidable blocks 30 had to be displaced and to be fixed by tightening the screws or to be released by loosening the screws.

The slidable block 3, 4 might however be arranged in a similar manner as the slidable 35 block 8 so that its position is controlled by a spring. Handles might be arranged in the slidable blocks to facilitate the movement of the blocks in outward direction against the action of the springs.

40 The second form of construction shown in Figs. 4 and 5 differs from that shown in Figs. 1-3 in that for each of the wire loops or rings 6 and 6^a two transverse arms 11 are substituted which are mounted in the slid- 45 able blocks 3 and 8 respectively. These transverse arms 11 are bent at their ends upwardly so that bearing angles 12 and 12^a (Fig. 5) are formed which are designed to hold the plates 10 at their edges without 50 touching the surfaces of the plates.

Owing to these arms 11 the device may be used for very large-sized plates which require to be supported at points of the edges which are at a great distance from one 55 another.

Having now particularly described and ascertained the nature of my said invention, I declare that what I claim is:—

60 1. A whirling device for plates with light-sensitive layers for equally distributing and drying said layers having a vertical shaft to be revolved, arms fixed to said shaft and blocks arranged on said arms, holders for the plates arranged on said blocks in such a manner that they will grip and hold the

plates from two diagonally opposite corners thereof.

2. A whirling device for plates with light-sensitive layers for equally distributing and drying said layers having a vertical shaft, 70 two guide arms fixed on opposite sides of said shaft and slidable blocks arranged on said guide arms, a pair of holding arms for the plates fixed on each of said slidable blocks in such a manner that each pair of 75 holding arms may grasp the plate across one corner thereof.

3. A whirling device for plates with light-sensitive layers for equally distributing and drying said layers having a vertical shaft, 80 two guide arms fixed on opposite sides of said shaft and slidable blocks arranged on said guide arms, a pair of holding arms for the plates fixed on each of said slidable blocks in such a manner that each pair of 85 holders may grasp the plate across one corner thereof, said holding arms for the plates being formed from angularly bent wire vertically arranged on said blocks.

4. A whirling device for plates with light-sensitive layers for equally distributing and drying said layers having a vertical shaft, 90 two guide arms fixed on opposite sides of said shaft and slidable blocks arranged on said guide arms, a pair of holding arms arranged on each of said slidable blocks for grasping and holding one corner of the plate, 95 each of said pairs of holding arms being formed by a single piece of wire, said piece 100 of wire being bent in the form of a loop.

5. A whirling device for plates with light-sensitive layers for equally distributing and drying said layers having a vertical shaft, two guide arms fixed on opposite sides of 105 said shaft and slidable blocks arranged on said guide arms, a pair of holding arms for the plates fixed on each of said slidable blocks in such a manner that each pair of holding arms may grasp the plate across one corner thereof, said holding arms for the 110 plates being formed from angularly bent wire vertically arranged on said blocks, a spring member connected with at least one of said pairs of holding arms, said spring member tending to draw said pair of holding 115 arms with their slidable block in the direction to the centre shaft.

6. A whirling device for plates with light-sensitive layers for equally distributing and drying said layers having a vertical shaft, two guide arms fixed on opposite sides of said shaft and slidable blocks arranged on said guide arms, a pair of holding arms for the plates fixed on each of said slidable blocks in such a manner that each pair of holding arms may grasp the plate across one corner thereof, said holding arms for the plates being formed from wire, said wire 125 being angularly bent and arranged vertically on said slidable blocks, a spring tending to 130

draw at least one pair of said holding arms with their slidable block in the direction to the revoluble vertical shaft.

7. A whirling device for plates with light-sensitive layers for equally distributing and drying said layers having a vertical shaft, two guide arms fixed on opposite sides of said shaft and slidable blocks arranged on said guide arms, one of said slidable blocks

being adjustable, a pair of holding arms for the plates fixed on each of said slidable blocks in such a manner that each pair of holding arms may grasp the plate across one corner thereof.

In testimony whereof I have hereunto set my hand.

LOUIS MUELLER.
